UNITED STATES PATENT OFFICE.

IRA A. MILLIRON, OF NEW YORK, N. Y., ASSIGNOR TO HAMMOCK EGG CARRIER COMPANY, OF BUFFALO, NEW YORK, A CORPORATION OF NEW YORK.

PROCESS FOR PACKING ARTICLES.

1,220,670.

Specification of Letters Patent. Patented Mar. 27, 1917.

Application filed July 31, 1914. Serial No. 854,281.

To all whom it may concern:

Be it known that I, IRA A. MILLIRON, a citizen of the United States, residing at New York city, in the county of New York and State of New York, have invented new and useful Improvements in Processes for Packing Articles, of which the following is a specification.

My invention relates to an apparatus and method for inclosing the eggs in suitable containers in which they may be transported and is particularly adapted to the shipping of eggs in small quantities by parcel post, etc., to be sent direct from the producer to the consumer, thereby making it possible for the producer easily and at short intervals to supply the consumer with absolutely fresh eggs without the interposition of the middleman. By this means the price to the consumer will be lowered, commonly below that of ordinary eggs, and the profit to the producer may be increased.

In my process an envelop consisting of a strip of suitable paper, or other suitable yielding material, is provided and preferably is moistened, either with water or some preservative solution to preserve the eggs and to render the paper more plastic and easy to handle. On the strip of paper so prepared and suitably supported are deposited any desirable number of the articles to be wrapped, that is as many as will equal the capacity of the particular container in question.

The sides of the envelop are then folded over and pressed around the individual eggs, and this having been done, one end of the envelop is held and the other is twisted, whereby twists are formed therein at each end and between the eggs, and the wrapping is completed and this most securely, and there is formed, so to speak, a "rope" of eggs adapted to be transferred to the container, specially made to receive the rope, and provided with notches or suitable seats formed to receive the twists between the eggs, and suitably spaced to receive the eggs between adjacent seats.

I have shown in the drawing herewith a suitable mechanism for practising this process and a suitable container to receive the rope of eggs. The same reference numerals indicate the corresponding parts in the va-

rious figures. Figures 1 and 2 are respectively top plan and side elevation of a wrapping mechanism. Fig. 3 is an enlarged isometric view of one end of said mechanism, with portions in section, to show the form of the supporting slides. Figs. 4 and 5 are respectively longitudinal and cross sections of a suitable form of container.

Referring first to the machine for packing this is not essential to the practising of the process here described, for that may be practised by hand, with or without the assistance of machines of various forms, but the machine here shown is light, simple, clean and convenient, economical to manufacture and easy to transport. It may be made more or less of wood but, as here shown is made wholly of thin metal and suitably finished, painted or japanned.

1 indicates the base preferably provided with short legs 2 extending on each side to give a firm support. To grooves 3 on the edges of the base are fitted the horizontal feet 5 of the slides having standards 6 upwardly extending therefrom and formed with curved recesses 7 having notches 8 at their centers, first to receive the envelop and shape the same into a sort of a trough into which the eggs are placed and next to receive the twists 9 after they have been formed by the torsion, applied by any suitable means, for instance the handle 10 journaled in a bearing 11 at one end of the base and provided with a clip 12 to grip the end of the envelop 15.

The other end of the envelop is twisted around the outside of the end standard and caught into the notch 16 there provided to receive it. Said end standard is also provided with the tongue 17 bent to engage with the edge of the base, and act as a sort of a lock.

The minimum distance between the slides is regulated by the length of the foot which engages the adjacent slide, and the maximum, by a strap 20 on the foot having a head 21 engaging with a slot 22 in the adjacent slide.

It will be noticed that the entire series of slides is divided into groups of four, all spaced uniformly, except that the spaces between the groups are larger. This is for the purpose of providing between each group

of four eggs a longer twist 40 to permit of the arrangement in the container as will be described.

The container as here shown comprises 5 heads 30 preferably circular, (but may be otherwise shaped, for instance square) and made of thin metal, wood, heavy cardboard or other suitable material. These heads are connected by the supporting elements or 10 strips 31 of suitable material, here shown of wire corrugated to form notches or depressions 32 providing seats to receive the twists and support the eggs in the envelop suitably spaced, so as to be suspended on the wires as 15 in a hammock out of possible contact with each other and so as to be protected from external injury.

The strips are connected to the heads by 20 bent ends 34 forming resilient hooks or clamps and provided with eyes 35, which extend outwardly through the inclosing cover 37, when the latter made of stiff paper corrugated board or other suitable material, is wrapped around the container. Through 25 these eyes may be drawn cords 38 for securing the cover in position, after the rope of eggs has been coiled around the strips.

These containers may be of any suitable 30 size to contain several dozen eggs. In the size here shown only one dozen is provided for, the eggs being arranged four in each row or transverse plane. Where the rope passes from one row to the next, the interval is longer and therefore to span the same 35 there must be a longer twisted portion as indicated at 40. To form such longer twists, a longer interval is provided between the groups of slides, as indicated in Figs. 1 and 2, where twelve slides are shown, four in 40 each group.

Of course the torsion might be applied to both ends simultaneously but in reverse di-

rections. However that would be merely an equivalent of holding one end and twisting the other and would not be so convenient.

45

Having described my invention, I claim,

1. The process of packing eggs for transportation comprising placing the eggs, suitably spaced, on a piece of flexible material, folding the material over the eggs to inclose 50 them in an envelop, applying torsion to the material firmly to inclose the eggs and to twist the portions of the material between the eggs, and then supporting the eggs in a suitable container at said intermediate 55 twisted portions of the envelop, substantially as described.

2. The process of packing eggs in a paper envelop, comprising first wetting a strip of suitable paper, then depositing the eggs 60 thereon in a row suitably spaced, then folding the paper around the eggs to form an envelop, then applying torsion to one end of the envelop and holding the other end to twist the portions of the envelop between the eggs.

3. The process of packing eggs for transportation comprising first wetting a strip of suitable paper, placing the eggs, suitably spaced, thereon, folding the paper over the 70 eggs to inclose them in an envelop, applying torsion to the paper firmly to inclose the eggs and to twist the portions of the paper between the eggs and supporting the eggs in a suitable container at said intermediate 75 twisted portions of the envelop substantially as described.

In testimony whereof I have signed my name to this specification in the presence of two subscribing witnesses.

IRA A. MILLIRON.
